E. A. DUNNING,
CORSET AND FASTENER THEREFOR.
APPLICATION FILED NOV. 10, 1919.

1,357,694.

Patented Nov. 2, 1920.

UNITED STATES PATENT OFFICE.

ELIZA A. DUNNING, OF CHICAGO, ILLINOIS.

CORSET AND FASTENER THEREFOR.

1,357,694.

Specification of Letters Patent. Patented Nov. 2, 1920.

Application filed November 10, 1919. Serial No. 336,811.

To all whom it may concern:

Be it known that I, ELIZA A. DUNNING, a citizen of the United States, residing at Chicago, in the county of Cook and State of

Illinois, have invented new and useful Improvements in Corsets and Fasteners Therefor, of which the following, when taken in connection with the drawing accompanying and forming a part hereof, is a specification.

10 My invention relates to a corset, and particularly to the means of fastening together adjacent edges thereof.

Among the objects of this invention are, to obtain a fastener which will enable the 15 person using the same to expeditiously join the adjacent edges of the corset, and which, when joined will obtain a secure and certain fastening; to obtain a fastener which is economical and one which is easily operated; 20 to obtain a fastener which will not make a noticeable protuberance on the garment placed thereover, as the same is worn; and to obtain a fastener which will, when the corset is not in use, present no fingers or 25 blade members extending beyond the edges which are to be joined thereby.

To accomplish the objects of my invention I employ a series of members preferably made of sheet metal which at equi-distant 30 points, in opposing pairs, along each edge of the corset, are fastened to the steels or stays of the corset. These members are so fastened as to allow or permit, a cord or lacing to be passed or drawn between them and 35 the steel or stay of the corset to which they are fastened.

I illustrate a construction embodying this invention in the drawing hereinabove referred to, in which—

40 Figure 1 is a front elevation of a corset embodying this invention:

Fig. 2 a top plan view of one of the duplicate members forming elements of the invention; and

45 Fig. 3 a vertical section, on line 3—3, of Fig. 2, viewed in the direction indicated by arrows;

Fig. 4 a top plan view of a modification of the member illustrated in Figs. 2 and 3; and

50 Fig. 5 a side elevation thereof.

A reference character applied to designate a given part indicates said part throughout the several figures of the drawing wherever the same appears.

55 A represents a corset. B, B', represent, respectively, the edges of the corset, which,

when the corset is in use are adjacent to each other, and are there secured by the devices illustrated in Figs. 2, 3, 4 and 5. These edges, as is well known, comprise flat sheet metal strips, which are termed steels or stays, and which are contained within a hem or fold of the corset provided therefor. D, D', represent members which are duplicates, and which are respectively secured on edges B, 60 B', in a manner to obtain rights and lefts in appearance. The members D, D', respectively comprise a base, d, a curved portion d', and a tongue member d² which is provided with an upturned end d³. Members 65 D, D', are rigidly secured to the edges B, B', as by rivets C, C, which extend through apertures C', C', provided therefor in base d, (Fig. 2), and the metal steels or stays of the corset, respectively. 75

E, E, represent apertures in edges B, B', respectively, said apertures being positioned at the upper and lower ends of said edges; and E', E', represent additional apertures, which are positioned midway of said ends. 80

F represents a cord which is adapted to engage with the members D, D', as the corset is placed, for use, on a person, as is about to be described.

Commencing, say, at the apertures E, E, 85 at the upper ends of the edges of the corset, the two ends of the cord F are passed through said apertures, from the rear to the front, and thereafter said cord is engaged with fasteners D, D', adjacent to said apertures, by passing it under the raised ends d³, of finger or tongue d², of said fasteners, on opposite edges relative to said apertures. That is, the cord extending through the aperture in edge B is passed under the finger 95 or tongue of fastener D', on edge B', and the end of said cord which extends through the aperture in edge B' is passed under the finger or tongue of the fastener on edge B. The cord is then engaged in a similar way 100

with the fingers or tongues of the remaining fasteners, and drawn taut, to bring said edges B, B', in relative position to suit the desire of the person using the corset, until it is desired to join the ends of the cord by 105 a knot, as at G, Fig. 1. At times the said knot G is made midway between the ends of the edges B, B', as is indicated by broken lines G', Fig. 1; and when said knot is so made an additional cord (F'), indicated by 110 broken lines in Fig. 1, is passed through the apertures E', E', and with said additional

cord (F'), the same operation is effected as hereinbefore recited relative to cord F; and an additional knot is made at the lower end of said edges.

5 It is to be understood that the winding of the cord F, (or F'), around members D, D', is permissible, but is not essential; and midway of the corset illustrated, in Fig. 1, I have illustrated the cord as not wound around the fingers of said members; being simply passed thereunder and across to the opposite edge, being there also passed under said fingers.

15 It will be observed that the bend, d', is curved in a plurality of planes, so that the cord F, (F'), may slide easily over or along said curve, without cutting or tearing the fiber of the cord.

20 In the modification illustrated in Figs. 4 and 5, the fastener, designated D², is made of wire which is bent up to obtain the base provided with apertures C², C², said base

being designated h, and provided with a raised portion h', corresponding with curve d' of fastener D, finger or tongue h² corresponding with finger or tongue d², and the raised end h³, corresponding with the end d³. The fastener D² is secured to the corset edge by rivets extending through apertures C², C², and through similar apertures in the 30 steel or stay of said edges, in the same manner as are fasteners D and D'.

I claim;

A corset fastening member, comprising a base, a curved element adjacent to said base, 35 said element being curved in a plurality of planes, and a finger extending from said curved element, with the end of said finger curved on the side thereof on which said curved element is placed.

ELIZA A. DUNNING.

In the presence of—

CHARLES A. BOOS,

RUTH NELSON.
